UNITED STATES PATENT OFFICE

162,768

HOUSING FOR KNIFE SHARPENERS

Alfred E. Anheuser, West Allis, Wis.

Application November 1, 1950, Serial No. 12,812

Term of patent 14 years

(Cl. D37—1)

To all whom it may concern:

Be it known that I, Alfred E. Anheuser, a citizen of the United States, residing at West Allis, in the county of Milwaukee and State of Wisconsin, have invented a new, original, and ornamental Design for Housing for Knife Sharpeners, of which the following is a specification, reference being had to the accompanying drawing, forming part thereof.

Figure 1 is a front perspective view of a housing for knife sharpeners, showing my new design;

Figure 2 is a rear perspective view thereof;

Figure 3 is a top plan view thereof;

Figure 4 is an end elevational view thereof looking at the right end in Figure 1; and

Figure 5 is an end elevational view thereof looking at the left end in Figure 1.

I claim:

The ornamental design for a housing for knife sharpeners, as shown.

ALFRED E. ANHEUSER.
